UNITED STATES PATENT OFFICE

2,539,373

PREINDEXING APPARATUS FOR STOP BARS
OF PAPER-CUTTING MACHINESMortimer S. North, Baltimore, Md., assignor to
The United States Printing and Lithograph
Co., Norwood, Ohio, a corporation of Ohio

Application October 25, 1947, Serial No. 782,137

8 Claims. (Cl. 33—181)

1

This invention relates to apparatus for setting up or pre-indexing a series of fixed positions of various measurements for use in connection with a paper cutting machine or the like.

One of the objects of the invention is to provide means for eliminating "down time" of a cutting machine or the like during the process of setting up or pre-indexing the stop bar of the machine.

Another object is to provide means whereby a plurality of stop bars may be pre-indexed simultaneously, independently of the paper cutting machine.

A further object is to provide means whereby the stop bar of a paper cutting machine may be quickly and accurately set up or pre-indexed by unskilled or inexperienced operators in advance of use of the stop bar upon the cutting machine.

These and other objects and advantages are attained by the means described in the following specifications and illustrated upon the accompanying drawings, in which:

Fig. 1 is a fragmental front elevational view of the pre-indexing machine, with parts broken away for clarity of disclosure.

Fig. 2 is a fragmental end elevational view of the machine.

Fig. 3 is a fragmental perspective view showing the general construction of the carriage, which forms part of the invention.

In the mass production of certain kinds of printed matter, such as labels for canned milk, canned fruits and vegetables, and the like, stacks of large sheets of printed or lithographed labels are first cut into long strips by one cutting machine, and then the strips of labels are cut or "chopped" into stacks of individual labels by another machine, commonly called a "chopper."

The last named cutting machine or "chopper" is generally equipped with a rotatable indexed stop bar provided longitudinally with a series of stop lugs spaced apart at fixed positions corresponding to the dimensions of the labels to be cut successively from the long strip of labels. In the past it was necessary to fix the stop lugs on the stop bar in their proper positions while the stop bar was in operating location upon the cutting machine. This entailed a great amount of "down time" for the cutting machine during the setting-up operation, idling all the workers assigned to the machine during this period.

The present invention permits a set-up man to set up or pre-index a stop bar independently of the cutting machine, thus making it possible for the cutting machine to continue operations on another set of labels without loss of production

2

time for the cutting machine operator and the various other workers assigned to wrap or otherwise process the labels as they are "chopped" from the long printed strips.

Referring to Fig. 1, the device of the present invention may be in the form of a table 8, comprising an elongated bed 9, supported by legs 10. A pair of brackets 12 and 13 support one or more stop bars 14. These stop bars are standard equipment on paper cutting machines, therefore they form no part of the present invention. As shown in Fig. 2, the brackets 12 and 13 are mounted at the rear of the table 8, and overhang the bed 9, mounting means being indicated at 17. A carriage 15 is mounted for longitudinal movement upon the bed 9 by means of wheels or rollers 16 which track upon the upper surface of the bed.

The stop bars 14 are provided with a plurality of splines or longitudinal grooves 18 which are adapted to receive stop lugs 19, slideable in the grooves and fixed therein at positions to designate the various widths of labels to be cut from the printed strips. Each groove upon the bar may be set with stop lugs for a different label, making it possible to use one bar for as many different jobs or labels as there are grooves in the bar.

The bar supporting brackets 12 and 13 shown in Fig. 1 are adapted to receive two stop bars 14 in parallelism, one above the other, so that two bars may be set up simultaneously for label jobs large enough to justify the use of two or more cutting machines. The right end of each bar 14 is supported upon a stud 20 axially extending inwardly from the sprocket shafts 21 rotatably mounted in the bracket 13. Pins 22 fix the bars 14 for rotation with the shafts 21. The opposite end of each bar 14 is supported in a half bearing 23, inwardly extending from the bar supporting bracket 12 and in axial alignment with its corresponding sprocket shaft 21. Displacement of the stop bars 14 from the brackets 12 and 13 may be precluded by suitable means, such as spring urged plungers 24 which engage a socket provided in the end face of each bar. The plungers 24 may be locked in holding position by means of thumb screws 25 threaded into the bracket 12 for contact with said plungers.

The outer right end of each shaft 21 is provided with a sprocket 28, said sprockets being engaged by the chain 29, so that the stop bars may be rotated simultaneously, rotation being effected manually. Chain tensioning means may be provided, such as the roller shown at 30 in Fig. 2 by way of example.

Before the splined stop bars may be rotated, the pawl 31 is to be disengaged from the index wheel 32, mounted on the upper sprocket shaft 21, the index wheel being in substantial abutment with the outer face of the bracket 13. The periphery of the index wheel 32 is provided with a plurality of notches 33 equal in number to the splines or slots in the stop bars 14. The pawl 31 may be disengaged from the index wheel by means of a hand lever 34. With the pawl disengaged, the upper bar 14 may be rotated until the spline to be set with stop lugs 19 is in line with the setting trigger 36 pivotally mounted on the upright post member 38 of the carriage 15. The pawl is then permitted to engage the corresponding peripheral notch 33 in the index wheel, thereby precluding further rotation of the stop bars 14. Yielding means to maintain engagement of the pawl with the index wheel may be provided, such as the tension spring 39, having one end secured to the pawl 31 and the opposite end secured to the bracket hub 40.

As hereinbefore explained, the carriage 15, with its upright post member 38, is longitudinally movable upon the bed 9. Fixed to the under side of the carriage 15 and movable therewith are the label strip carrier bars 41, disposed in longitudinal ways 42, Fig. 3. The strip carrier bars 41 are of substantially greater length than the printed strip of labels which is to be cut or "chopped" by the cutting machines upon which the stop bars 14 are to be used.

Each side of the bed 9 is provided with a longitudinal ledge 43, surmounted by a retaining strip 44 substantially overhanging the inner margin of each ledge, thus serving to confine the carriage within the bed of the table 8. A scale 45 is mounted upon the front retaining strip 44 longitudinally thereof, and is provided with calibrations 46. The scale may be fixed by means of screws, such as 48, which serve also to fix the retaining strips 44 to the ledges 43.

A fixed indicator 49 is mounted on the carriage 15, having a pointer 50 adjacent the inner edge of the scale 45 and substantially flush with the top thereof. A second indicator 51 is mounted upon the carriage, said indicator being provided with a frictionally adjustable pointing arm 52 overhanging the inner margin of the scale and in slidable contact therewith.

The upright post member 38 is longitudinally adjustable upon the carriage 15, being slidable in the carriage grooves 53. Adjusting means may comprise a knurled screw 54 at the rear of the post, the turning of which will move the post 38 to the right or left. Adjustments of the post 38 may at times be necessary to compensate for variations in the castings of cutting machines upon which the stop bars 14 are used. Clamping means, such as the lock screw 55, may be provided for clamping the post 38 against further movement on the carriage 15 after proper adjustments have been made.

In addition to the pivotally mounted setting trigger 36, an auxiliary setting trigger 56 is also pivotally mounted in the post member 38, in vertical alignment with the trigger 36, the pivoting means for both triggers being indicated at 58. Each trigger has a contact face 59 at its outer end, against which the stop lugs 19 abut when said lugs are positioned and fixed in the splines or grooves 18 of the stop bars. A retaining plate 60, mounted upon the trigger post 38 by suitable means, such as screws 61, serves to preclude sidewise movement of the setting trigger 75 for indexing the second cut, the setting triggers

members 36 and 56. Since the setting triggers must be moved over the stop lugs 19 after each lug is fixed in its proper position, lifting means may be provided in the form of a trigger tab 62 upon the trigger 36, as shown in Figs. 2 and 3. Pivotal movement of trigger 36 is translated to the auxiliary trigger 56 by means of a vertical connecting link 63, which connects the two triggers for unitary pivotal action, as shown upon the drawings.

Near the right end of the bed 9 a knife gauge 65 is provided, as shown in Fig. 3. One edge 66 of the knife gauge is at substantial right angles to the longitudinal axis of the bed 9, and represents the position of the cutting machine knife relative to the stop lugs 19 on the stop bars 14. The knife gauge 65 may be mounted for longitudinal adjustment upon an inner face of a table ledge 43 by means of screws 67 inserted through an elongated slot 68 and threaded into the ledge 43. In order to permit a strip of labels 69 Fig. 1, to be inserted under the knife gauge 65 for gauging purposes, the gauge is mounted in slightly elevated position relative to the upper surface of the strip carrier bars 41, as shown in Fig. 1.

The forward edge 70 of the carriage 15 serves as an abutment for an edge 71 of the label strip used in setting up the stop bars 14. Means for maintaining the label strip edge in abutment with the carriage edge 70 may be provided, such as the hold down clip 72 having a gripper portion 73 in yielding contact with the upper face of a strip carrier bar 41. The clip 72 may be secured by means of a screw 74, Fig. 3, to the upper surface of the carriage 15. The up-turned free end 75 of the hold down clip may be used for manually raising the clip out of contact with the strip carrier bar for insertion or removal of the label strip 69 thereunder.

Operation of the instant invention is as follows: With one or more stop bars 14 supported between the brackets 12 and 13, each bar having an empty or unused groove or spline 18 substantially tangent to end faces of the setting triggers 36 and 56, one end of a label strip 69 is placed against the carriage edge 70 and under the hold down clip 72. The opposite end of the printed strip is fed under the knife gauge 65, the entire strip being flattened upon the strip carrier bars 41. The carriage 15 is then moved to the left until the first cut to be made from the strip is located in alignment with the gauging edge 66 of the knife gauge. With the carriage in this position, a stop lug 19 is slidably moved to the left against the contact face 59 of the trigger 36 and firmly held against said trigger while the stop lug screw 76 is tightened by means of a suitable wrench to fix the stop lug against movement in the groove or spline 18. If both stop bars 14 are to be set up for the same cutting or chopping job, a stop lug 19 in the lower stop bar 14 is also positioned in the same manner just outlined.

After the first cut is thus located, the position of the pointer 50 relative to the calibrations 46 on the scale 45 should be noted. If the pointer 50 should be on an uneven calibration, the frictionally movable pointing arm 52 is moved to the right or left, as the case may be, to the nearest even calibration on the scale 45. The size of each label to be cut from the strip being known, the carriage 15 is then moved to the left the required number of inches for indexing the second cut. Before the carriage is moved

36 and 56 are raised to clear the stop lugs 19 which have been set for the first cut. This is done by depressing the trigger tab 62 while the triggers 36 and 56 pass over the stops 19 on movement of the carriage 15. The trigger tab 62, 5 of course, must be depressed each time the carriage is moved past a fixed stop lug.

After the second cut has been located, another stop lug 19 is brought against each trigger 36 and 56 and tightened in the same manner as 10 explained above. This procedure is repeated for each cut until all the cuts on the strip have been indexed. The stop bars 14 are now ready to be removed from the brackets 12 and 13 and delivered to the cutting or chopping machines upon which the labels used for setting up the stop bars are to be cut. During the period required for setting up the stop bars just described, the cutting machines or choppers upon which they are to be used may be operating upon another set of labels with a different stop bar set up for that particular job, thus eliminating any down time while preparations are being made for the next job.

After one set-up has been made upon one or more bars by means of the instant invention, it may be desirable to make one or more additional set-ups on the same bars. In that case, the stop bars between the brackets 12 and 13 are rotated in the manner hereinbefore described to bring a free slot 18 in each bar tangent to the triggers 36 and 56. The printed strip 69 used for the previous set-up is removed, another strip inserted, and the foregoing procedure followed.

The advantages of the present invention are therefore readily to be appreciated, since a cutting machine or chopper may be devoted entirely to production without loss of down time for setting up. When one job of cutting labels, tags or the like has been completed, the operator removes the stop bar from his machine and simply replaces it with a pre-indexed stop bar and proceeds immediately with the next job of cutting. It is possible to have any number of pre-indexed stop bars in readiness for successive cutting jobs.

While the cutting of printed or lithographed labels has been used as an example for explaining the instant invention, it is to be understood that the device is not necessarily limited to such use. The device is equally adapted for use in setting up or pre-indexing stop bars for playing cards, unprinted sheets, textiles, and other materials.

It is to be further understood that various structural changes and modifications are possible within the scope of the appended claims, without departing from the spirit of the invention.

What is claimed is:

1. Pre-indexing apparatus for locating the stops upon a stop bar, comprising in combination, an elongated table and a carriage slidable lengthwise thereon, said carriage including an upright post, an elongated specimen strip carrier movable with the carriage, and means for holding a strip in a predetermined position of lengthwise adjustment with respect to the carrier, bracket means fixed relative to the table for supporting a stop bar in parallelism with the line of movement of the carriage, a setting trigger having an abutment for contacting and locating a stop on the bar, and means mounting the trigger upon the post for displacement of said abutment from proximity with the stop, indicator means upon the carriage, and a scale on the

table cooperating with said indicator means to show various positions of the carriage upon the table, means causing the specimen strip to move with the carrier in flatwise contact thereon, and an index member fixed relative to the table overlying the path of movement of the strip carrier and corresponding in position with the position of a cutter relative to the strip, when duplicates of the strip are fed into a cutting machine in a manner determined by the stops of the stop bar.

2. Pre-indexing apparatus for locating the stops upon a stop bar, comprising in combination, an elongated table and a carriage slidable lengthwise thereon, said carriage including an upright post, an elongated specimen strip carrier movable with the carriage, and means for holding a strip in a predetermined position of lengthwise adjustment with respect to the carrier, bracket means fixed relative to the table for supporting a stop bar in parallelism with the line of movement of the carriage, a setting trigger having an abutment for contacting and locating a stop on the bar, and means mounting the trigger upon the post for displacement of said abutment from proximity with the stop, indicator means upon the carriage, and a scale on the table cooperating with said indicator means to show various positions of the carriage upon the table, adjustment means for positioning the post at different locations upon the carriage, means causing the specimen strip to move with the carrier in flatwise contact thereon, and an index member fixed relative to the table overlying the path of movement of the strip carrier and corresponding in position with the position of a cutter relative to the strip, when duplicates of the strip are fed into a cutting machine in a manner determined by the stops of the stop bar.

3. Pre-indexing apparatus for locating the stops upon a stop bar, comprising in combination, an elongated table and a carriage slidable lengthwise thereon, said carriage including an upright post, an elongated specimen strip carrier movable with the carriage, and means for holding a strip in a predetermined position of lengthwise adjustment with respect to the carrier, bracket means fixed relative to the table for supporting a stop bar in parallelism with the line of movement of the carriage, a setting trigger having an abutment for contacting and locating a stop on the bar, and means mounting the trigger upon the post for displacement of said abutment from proximity with the stop, a stationary scale arranged upon the table lengthwise thereof, a fixed indicator on the carriage including a pointer directed at the scale, a movable indicator attached to the carriage slidable in the direction of carriage movements and including a second pointer directed to the scale at a distance from the first pointer, means causing the specimen strip to rest flatwise upon the carrier and to move therewith as the carrier is shifted, and an index member fixed relative to the table in spaced overlying relation to the carrier and the strip superposed thereon, said member corresponding in position with the position of a cutter as related to the strip when advanced through a cutting machine.

4. Pre-indexing apparatus for locating the stops upon a stop bar, comprising in combination, an elongated table and a carriage slidable lengthwise thereon, said carriage including an upright post, an elongated specimen strip carrier movable with the carriage, and means for holding a strip in a predetermined position of length-

wise adjustment with respect to the carrier, bracket means fixed relative to the table for supporting a stop bar in parallelism with the line of movement of the carriage, a setting trigger having an abutment for contacting and locating a stop on the bar, and means mounting the trigger upon the post for displacement of said abutment from proximity with the stop, a stationary scale arranged upon the table lengthwise thereof, a fixed indicator on the carriage including a pointer directed at the scale, a movable indicator attached to the carriage slideable in the direction of carriage movements and including a second pointer directed to the scale at a distance from the first pointer, means causing the specimen strip to rest flatwise upon the carrier and to move therewith as the carrier is shifted, and an index member fixed relative to the table in spaced overlying relation to the carrier and the strip superposed thereon, said member corresponding in position with the position of a cutter as related to the strip when advanced through a cutting machine, and adjustment means for positioning the upright post at varying distances from said member while the carriage is stationary.

5. Pre-indexing apparatus for locating the stops upon a stop bar, comprising in combination, an elongated table and a carriage slideable lengthwise thereon, said carriage including an upright post movable therewith, bracket means fixed relative to the table for supporting at least one stop bar in parallelism with the line of movement of the carriage, a setting trigger having an abutment for contacting and locating a stop on the bar, and means mounting the trigger upon the post for displacement of said abutment from proximity with the stop, indicator means upon the carriage, and a scale upon the table cooperating with said indicator means to show various positions of the carriage upon the table, an elongated strip carrier movable with the carriage, means for holding a flat specimen strip in a predetermined position of lengthwise adjustment with respect to the carrier to move with the carriage and along the table, and an index member fixed relative to the table in spaced overlying relation to the path of movement of the carrier, and corresponding in position with the position of a cutter as related to the strip when advanced through a cutting machine.

6. Pre-indexing apparatus for locating the stops upon a stop bar, comprising in combination, an elongated table and a carriage slideable lengthwise thereon, said carriage including an upright post movable therewith, bracket means fixed relative to the table for supporting at least one stop bar in parallelism with the line of movement of the carriage, a setting trigger having an abutment for contacting and locating a stop on the bar, and means mounting the trigger upon the post for displacement of said abutment from proximity with the stop, indicator means upon the carriage, and a scale upon the table cooperating with said indicator means to show various positions of the carriage upon the table, an elongated strip carrier movable with the carriage,

means for holding a flat specimen strip in a predetermined position of lengthwise adjustment with respect to the carrier to move with the carriage and along the table, an index member fixed relative to the table in spaced overlying relation to the path of movement of the carrier, and corresponding in position with the position of a cutter as related to the strip when advanced through a cutting machine, and a movable indicator attached to the carriage and slideable lengthwise of the carrier to register with graduations on the scale to translate complex fractional scale readings into simpler fractions to facilitate accurate successive advancements of the carriage along the table.

7. As a new article of manufacture, a device for spacing stops upon the stop bar of a chopping machine, and comprising in combination, a table, a carriage slideable lengthwise of the table, an index member on the table corresponding in location to the location of the blade of the chopping machine and overlying the path of movement of the carriage, means providing for lengthwise movement of a specimen strip with the carriage and along the table, and past said member, means for holding the strip in a predetermined position of lengthwise adjustment with respect to the carriage, means displaceably mounting at least one stop bar alongside the carriage for supporting said bar in parallelism with the line of carriage movement, and means on the carriage providing an abutment to contact and locate the stops upon the stop bar as the carriage is moved relative to said member.

8. As a new article of manufacture, a device for spacing stops upon the stop bars of chopping machines, and comprising in combination, a table independent of the chopping machine, a carriage slideable lengthwise of the table, an index member on the table corresponding in location to the location of the blade of the chopping machine and overlying the path of movement of the carriage, means providing for lengthwise movement of a specimen strip with the carriage and along the table, means for holding a strip in a predetermined position of lengthwise adjustment with respect to the carriage means displaceably mounting at least one stop bar along the table in parallelism with the line of carriage movement, and means on the carriage providing an abutment to contact and locate the stops upon the stop bar as the carriage is moved lengthwise of said bar.
